ATTORNEY.

UNITED STATES PATENT OFFICE.

LOLA R. BALDWIN, OF GALESBURG, ILLINOIS.

BOTTLE-CAP EXTRACTOR.

1,199,860.

Specification of Letters Patent.

Patented Oct. 3, 1916.

Application filed May 20, 1915. Serial No. 29,338.

To all whom it may concern:

Be it known that I, LOLA R. BALDWIN, a citizen of the United States, and a resident of Galesburg, in the county of Knox and State of Illinois, have invented a new and useful Bottle-Cap Extractor, of which the following is a specification.

My invention relates to devices for removing paper caps or stoppers from milk and cream bottles. Such caps are generally made of a good grade of pasteboard and are covered or saturated with paraffin or some kindred substance not only to render them moisture-proof but also to make them somewhat firm yet resilient. Thus they spring into place in the interior annular groove or seat in the neck of the bottle. Because of their being made to fit almost perfectly, and because of the above stated conditions, it is somewhat difficult to remove them, the attempt so to do being frequently attended by pushing the cap down into the cream, by tearing the cap, by splashing the cream, and by consequent loss thereof.

The principal object of my invention is to provide a simple, inexpensive, durable and easily operated tool or instrument, which is cleanly, which is sanitary, and which will lift the stopper from the bottle without any of the attendant ill results above described.

Another object is to provide an extractor the parts of which may with ease and facility be assembled, and which may as readily and facilely be taken apart for cleaning or for repairs.

To these ends the invention consists, substantially, in the improvements herein described.

By way of example a cap-extracting instrument constructed according to the invention is hereinafter described, with reference to the accompanying drawing, in which:—

Figure 1 is an elevation of the device in what I may term normal position, or position ready to pierce and be inserted through the cap; Fig. 2, a similar view, but the device turned partly around and the parts in position ready to extract the cap; Fig. 3, a longitudinal central section, the elements shown as in the same positions as in Fig. 2, and a bottle-cap shown as in position for being lifted or extracted; Fig. 4, an enlarged detail, partly broken away; and Fig. 5, is

an elevational view of a modification of the invention.

Considering the drawings in detail and referring to each element (and part thereof where required) by a distinguishing numeral, uniformly employed, 2 designates a tapered or conical tube, made preferably of thin, bright and sanitary metal and which may be either spun or made of sheet metal the edges of which are butted and then soldered together to provide a surface free from irregularities due to overlapping. The cone is truncated and to its vertex is soldered or otherwise secured a piercing or puncturing tip 3 of such shape and size as to preserve the continuity of the cone, and said tip is preferably made of steel or some other metal which will take and hold a very sharp point.

4 designates a top, suitably secured to and on the base of the cone, as by soldering, and is provided with a centrally arranged aperture for the passage of a rod or stem 5 the upper end of which is bent to form an eye 6.

7 designates an annular shoulder, formed either by swaging the rod or by a drop of solder.

The lower end of the stem 5 is flattened to provide a foot 8 having a transverse aperture into which is fitted and secured a pin 9.

10, 10 designate cap-lifting arms the inner end of each of which is bent to form an eye 11 which pivotally embraces one of the ends of the pin 9. In order to retain them on said pin its ends may be struck up or riveted. The end of the conical tube adjacent the piercing point 3 is provided with oppositely disposed small openings 15 through which the lifting arms 10 are adapted to be projected, and by reference to Figs. 1 to 3, inclusive, it will be seen that the ends of the arms 10 are beveled while the body portions are of sufficient cross-sectional area to cause the same substantially to engage frictionally

the side walls of the openings 15 to prevent the entrance of any matter within the tube 2. As shown in Fig. 11, the beveled ends of the arms 10 normally lie exposed in the openings 15 with the outer ends flush with the outer wall of the tube so as to obviate danger of the arms injuring adjacent articles and also to provide a constant closure for the openings 15. It will be readily understood in using the device that the cleaning of the arm ends is accomplished when the

sides of the tube 2 are cleaned, as by rubbing the same with a cloth, and the inner ends of the arms being protected by being inclosed within the tube, it will not be necessary to 5 project the same for cleaning as in previous devices.

In the modification, Fig. 5, I have shown a cylindrical tube 12 having a tapered lower end 13 to which the point or tip 3 is suitably 10 secured. 14 indicates a removable top screwed onto the upper end of the tube 12. To remove a cap or stopper from a bottle the point 3 is first inserted through it. Because 15 of the sharpness and the conical shape of the point this is accomplished by using only a very slight pressure—by no means sufficient to dislodge the cap. The instrument will be pushed down until the openings 15 lie just 20 below the cap, when the operator, one of whose fingers is inserted through the eye 6 while other fingers and the thumb are clasping the tube 2, will press downwardly on said eye to depress the relatively movable elements to cause the arms 10 to pass in contact with and over the lower edges of and 25 out through the apertures 15, the normal positions of the tips of the arms being flush with the metal about said apertures. This will throw the arms to the positions shown 30 best in Fig. 3. The operator will now, while bearing on the eye 6 with sufficient force to maintain the elements in the relative positions just described, lift on the tube 2, whereby the arms 10 will bear upwardly 35 on the lower face of the cap (indicated by 16, Fig. 3) and raise it from its seat in the neck of the bottle. The operation is performed in an instant. The cap is pierced and lifted so easily and effectively that there 40 is no attendant danger of either pushing it into the cream, of splitting the cap, or of spilling or splashing the cream. The cap may be removed from the stem by raising the latter relatively to the tube and then 45 pushing the cap off the point. The rod 5 and the elements carried thereby may be inserted upwardly from the bottom of the tube before the point 3 is secured thereto, in

which event the eye 6 is formed after the end of the rod is passed through the aperture in the top 4. Or the rod and its attached parts may be inserted downward through the tube before the top is secured thereto. To disassemble the device shown in Figs. 1, 2 and 3 it is necessary only to 55 apply sufficient heat to melt the solder, whereupon the rod and the elements carried thereby may be removed for repairs or for cleaning.

It will be quite evident that numerous 60 changes may be made in the details of construction from those shown, without departing from the spirit and scope of the invention.

Therefore, without limiting myself to details or particularities except where such are specifically pointed out, I claim as new the following, to-wit:—

As an article of manufacture, a bottle-cap extractor comprising a conical tube provided 70 with oppositely arranged apertures near its lower end, a top on said upper end, provided with a centrally arranged aperture, a piercing-point secured on the lower end of the tube, an operating-rod passing through said 75 aperture in the top, said rod provided at its upper end with an eye, intermediate its ends with a shoulder adapted to strike said top to limit its upward movement, and its lower end flattened, a pin secured transversely of 80 and to said flattened end, and cap-lifting arms having beveled outer ends adapted to lie flush with the outer wall of said conical tube secured on said pin each by bending it around one end portion of the pin, the free 85 end of each arm adapted to pass outward through one of said oppositely arranged apertures with the body-portion of each arm substantially frictionally engaging the side walls of the apertures to provide constant 90 closures therefor.

In testimony whereof I hereto subscribe my name this 12th day of May, 1915, at Galesburg, Knox county, Illinois.

LOLA R. BALDWIN.
